UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

ELEVATING MECHANISM.

Application filed June 17, 1921. Serial No. 478,424.

This invention relates to elevating mechanism and particularly, although not exclusively, to raising and lowering mechanism for kerf cutting mining machines, whereby 5 such a machine is enabled to cut kerfs in a mine face at any desired elevation or inclination to the horizontal, or whereby the unloading of the machine from its truck upon an elevated bench or the like, and the subsequent 10 unloading thereof, is facilitated.

The invention has for an object to provide improved manually operated means whereby a single operator can, with relatively slight exertion, readily raise or lower a relatively 15 heavy machine into any desired vertical position and as readily dispose the same in any desired inclination to the horizontal, said mechanism being of such a character as to permit a variable but equally effective operation 20 thereof in accordance with the strength of the operator or the conditions of use. Another object of the invention is to provide a mining apparatus comprising a mining machine and a truck therefor having means for 25 raising and lowering said machine with respect to the body of the truck, together with means for operatively connecting the machine with the wheels of the truck so as to propel the latter, said last named means being of 30 such a character as not to interfere with the operation of raising and lowering the machine, and being so arranged as to remain continuously operative in any vertical position 35 of said machine.

The foregoing and other objects of the invention, together with means whereby the same may be carried into effect, will best be understood from the following description of certain forms and embodiments thereof ill- 40ustrated in the accompanying drawings, in which,—

Fig. 1 is a side elevation of a truck mounted mining machine embodying the invention, the elevating mechanism being shown in longitudinal vertical section.

Fig. 2 is a side elevation of the same machine on a reduced scale, illustrating the operation of raising the machine.

Fig. 3 is a side elevation illustrating another form and application of the invention.

Fig. 4 is a rear elevation of parts shown in Fig. 3.

Fig. 5 is an enlarged transverse section of the elevating mechanism, taken substantially 55 on the line 5—5 of Fig. 3.

Fig. 6 is a horizontal section taken substantially on the line 6—6 of Fig. 5.

In Figs. 1 and 2 is shown a mining machine truck comprising a truck body 15 mounted on wheels 16 adapted to run on a suitable track 17. Operatively connected (by means hereinafter more fully described) with the truck body 15, which constitutes a lower support, is an upper support or frame 18 by which the mining machine is carried. In order to assist in steadyng the upper support 18, it is preferably normally connected with the lower support 15 by one or more telescopically adjustable rods or jacks 19.

Mounted on the support or frame 18 is a mining machine which, in the form of the invention shown in Figs. 1 and 2, is of the well-known unitary room and pillar type comprising a casing 20 provided at its forward end with a rigid, forwardly extending cutter bar 21 carrying the usual cutter chain 22, and at the rear end with a feed driving member, herein a sprocket 23 adapted to cooperate with the usual flexible feeding member or chain, both the cutter chain and the feeding member being driven in the usual manner and through suitable connections of well known construction and arrangement from a motor (not shown) in the casing 20. As is common in machines of this type, a turntable 26 is interposed between the support or frame 18 and the mining machine which is secured in place upon said support and turntable by any suitable means whereby the machine may cut while on the turntable or be 90 bodily removable therefrom for cutting on its own bottom, this means being well known in the art and not requiring description herein.

The mining machine is operatively connected with the axle 31 of one pair of truck wheels 16 by means whereby the power of the mining machine motor is utilized to propel the truck. As in a well known construction, a gear 27, carried by the machine and actuated through suitable connections (not shown) 100 from the motor, meshes, in the transport position of the machine, with a gear 27' carried by the frame or support 18 and operatively connected in the usual manner with a sprocket 28 carried by said frame or support. In accordance with one feature of the present invention, the sprocket or transmission element 28 is operatively connected with a sprocket or transmission element 29 on the axle 31 by power transmitting devices of such a charac- 110

ter as to permit both the vertical position of the support 18 with respect to the truck body, and the inclination thereof with respect to the horizontal to be varied without disturbing 5 the driving connections. In the construction shown, an arm 30 pivotally mounted at one end of the shaft of the sprocket 28 is pivotally connected by a stud 32 with one end of a second arm 33 which in turn is pivotally 10 mounted at its opposite end on the axle 31. The sprocket 28 is connected by a chain 34 with a double sprocket 35 carried by the stud 32 and coaxially disposed with respect thereto, said sprocket 35 being connected by a 15 chain 36 with the sprocket 29.

In accordance with another feature of the invention, the elevating mechanism for operatively connecting the upper support or frame 18 with the lower support or truck 20 body 15 comprises a plurality of spaced fluid pressure devices each comprising a cylinder and a piston therein, one of said elements being connected with and supported by the truck body 15 and the other of said elements 25 being connected with and supporting the frame 18. In the construction shown in Figs. 1 and 2, said elevating mechanism comprises vertically disposed, longitudinally spaced hydraulic cylinders 37 and 38 carried by the 30 truck body 15 and disposed respectively at opposite sides of the vertical line through the center of gravity of the machine supported on the frame 18 and at substantially equal distances from said line but relatively close 35 thereto. The cylinders 37 and 38 are provided with pistons 39 and 40, respectively, said pistons having piston rods 41 which are connected by transverse pivots 42 and 42' with one or more brackets or plates 43 carried 40 by the frame 18. The pivots 42 and 42' preferably engage slots 44 in the brackets or plates 43, said slots being slightly elongated in a direction longitudinal to the machine in order to permit the free operation of a mechanism 45 as hereinafter described. The cylinders 37 and 38 are preferably formed as integral parts of a casting 45 which also includes a reservoir 46 adapted to contain oil or other liquid and provided with a filling opening 50 normally closed by a plug or cap 47. The reservoir 46 communicates at its bottom, through suitably arranged passages, with the lower ends of both cylinders 37 and 38. In the construction shown in Fig. 1, said passages 55 are provided by pipes 48 and 49 having branches communicating with said reservoir and cylinders respectively. The pipe 48, which provides a fluid inlet passage, communicates between its ends with the reservoir 46 and at its ends with ports 50 formed in the lower ends of the cylinders and controlled by check valves 51 which open inwardly and toward said cylinders. The pipe 49 also communicates at its ends with the 60 lower ends of said cylinders and at an inter-

mediate point with the reservoir 46, communication with said reservoir being controlled by a manually operated valve 52. It will herein be noted that the valve 52 is of such construction that fluid cannot pass from one 70 cylinder to the other through pipe 49.

The mining machine is shown in Fig. 1 as in its lowermost position, and in order to elevate the same the valve 52 is closed, and the upper support or frame 18, together with the 75 machine carried thereby, is rocked or oscillated in a longitudinal vertical plane by grasping the forward end of the cutter bar 21 and tilting or pumping the same alternately upwardly and downwardly. Such 80 tilting or rocking of the machine is facilitated by the fact that, by reason of the location of the devices connecting the upper and lower supports in a position closely adjacent the center of gravity of the machine, said machine will be approximately balanced, so that very little effort is required in order to oscillate it. As the forward end of the cutter bar 21 is lifted, as shown in Fig. 2, the rear piston 39 being held against downward movement by the closure of the corresponding 85 check valve 51, the machine will rock about the rear pivot 42 as a center, thereby lifting the forward piston 40 and permitting liquid from the reservoir 46 to flow through the 90 pipe 48 and the corresponding check valve 51 into the lower end of the cylinder 38. When the forward end of the cutter bar 21 is depressed, the piston 40 will be held in the position into which it has been previously 95 moved, by the closure of its check valve 51 and the trapping of the liquid in the lower end of the cylinder 38, so that during this operation the machine will be rocked about the axis of the forward pivot 42', and the 100 piston 39 will be raised, drawing liquid into the lower end of the cylinder 37. It will thus be seen that by successive rocking movements of the machine by means of the cutter bar 21, the pistons 39 and 40 will be alternately and successively stepped upwardly, 105 resulting in an elevation of the upper support 110 and the machine carried thereby. It will be noted that when the machine has been brought to the desired elevation, the angular 115 position thereof with respect to the horizontal may be as readily determined by raising or lowering the forward end of the cutter bar 120 into the position desired. In order to lower the machine the valve 52 is opened, thereby permitting a free flow of liquid from the 125 lower ends of the cylinders back to the reservoir.

In the construction shown in Figs. 3 to 6, the elevating mechanism constituting the invention is shown as interposed between a mounted longwall mining machine and its 130 usual skid 53, said skid, which constitutes a lower support, being connected by said elevating mechanism with an upper support or 135

platform 54 carrying a turntable 55 upon which said machine is mounted. The machine as shown is of the well-known longwall type and comprises a casing 56 having at its 5 rear end the usual feed chain sprockets 57 and at its forward end a cutter bar 58 having a cutter chain 59, said cutter bar being angularly adjustable on the casing 56 into the longitudinal position shown or into positions transverse to said casing at either side thereof.

The elevating mechanism comprises a casting 60 supported by the skid 53 beneath the center of gravity of the machine and having 15 integral, upright cylinder portions 61 and a portion 62 between said cylinders or cylinder portions constituting a liquid reservoir. In the construction shown, four cylinders 61 are provided, said cylinders being arranged in 20 longitudinally spaced pairs, and the cylinders of each pair being spaced from one another transversely of the machine. The cylinders 61 are provided with pistons 63 provided at their upper ends with longitudinally slotted 25 ears 64, the ears of the pistons in the cylinders of each pair being connected with each other and with depending ears 65 on a plate 66 secured to the bottom of the support or platform 54 by means of transverse pivot pins 67. 30 The bottoms of the several cylinders 61 are provided with ports 68 controlled by inwardly opening check valves 69, and the port 68 of one cylinder of each pair is connected with the port 68 of the corresponding cylinder of the 35 other pair by a longitudinally disposed inlet passage 70 formed in the casting 60 and having a branch passage 70^a communicating with the interior of the reservoir 62. The bottoms of the two cylinders of each pair are connected by a transverse exhaust passage 71 formed in the casting 60, each of said passages 71 communicating with the interior of the reservoir 62 through a branch passage 72 controlled by a manually operated exhaust valve 73. 40

45 The operation of this form of the invention is substantially the same as that of the form of the invention first described, as will be obvious without further explanation in detail. It will be noted, however, that, by separate operation of the exhaust valves 72 and consequent release of the liquid in either pair of cylinders, the machine may be caused to assume any angular position with respect to the horizontal under the influence of gravity 50 after it has been elevated to a greater or less extent from its lowermost position.

55 It will also be observed that, in both forms of the invention, the operation of the mechanism to elevate the part to be raised is independent of the length of the tilting or rocking strokes imparted thereto by operating the cutter bar of the machine, so that a relatively large number of relatively short strokes, or a relatively small number of relatively long 60 strokes may be employed to produce a given

vertical movement in accordance with the strength or convenience of the operator, or the position occupied by the machine, which position may, in many instances, determine the length of the stroke permitted.

In order to assist in steadyng the machine shown in Figs. 3 to 6, and for the purpose of supporting the same independently of the elevating mechanism, thereby preventing the machine from settling by reason of leakage of 70 liquid from the cylinders 61, the skid 53 is provided at opposite sides of the rear and forward ends thereof with uprights 74 provided at their upper ends with guides 75 to receive depending legs 76 correspondingly positioned 75 on the upper support or platform 54, said guides being provided with means, as, for example, set screws 77, for clamping said legs and thereby rigidly connecting said platform with the skid 53. The guides 75 and legs 76 80 are preferably so constructed and arranged as to allow for relative movement thereof longitudinally of the machine, thereby permitting said machine to be tilted in a longitudinal vertical plane without disturbing the connections.

85 It will be obvious that the auxiliary supporting means last described may, if desired, be employed to equal advantage in the form of the invention shown in Figs. 1 and 2 in 90 substitution for the rods or jacks 19. Also, in the form of the invention first described, the hydraulic devices or cylinders will preferably be arranged in pairs, as in the form of the invention shown in Figs. 3 to 6, in order to 95 assist in steadyng the machine transversely.

100 While I have herein specifically described and shown in the drawings two forms which my invention may assume in practice, it will be understood that the particular constructions and arrangements described and shown have been chosen for illustrative purposes merely, and that the invention may be otherwise embodied and practiced without departing from its spirit or the scope of the claims 105 hereunto appended.

110 What I claim as new and desire to secure by Letters Patent is:—

115 1. In combination, relatively movable upper and lower frame elements and adjustable connecting means between said frames comprising relatively movable parts respectively operatively connected with said upper and lower frame elements and extensible by successive opposite movements of the upper frame, and means including a fluid for maintaining said parts automatically in different 120 relative positions on movement thereto.

125 2. In a mining apparatus, a support, cutting mechanism thereon, and hydraulic supporting means for the latter adjustable by successive tilting movements of the cutting mechanism and adapted to support the latter at different heights.

130 3. The combination with upper and lower

supports, of mechanism extensible by movement of one of said supports connecting said supports and comprising a plurality of longitudinally spaced cylinders connected to one of said supports, pistons in said cylinders, and transverse pivots connecting said pistons with the other of said supports.

4. The combination with upper and lower supports, of mechanism extensible to determine the plane of the upper support connecting said supports and comprising a casting carried by said lower support and forming a plurality of spaced cylinders and a liquid reservoir communicating with said cylinders, and pistons in said cylinders connected to said upper support for movement with the latter in either direction.

5. The combination with upper and lower supports, of mechanism extensible to determine the plane of the upper support connecting said supports and comprising a plurality of cylinders arranged in longitudinally spaced pairs, the cylinders of each pair being transversely spaced, and pistons in said cylinders connected to the other of said supports.

6. The combination with upper and lower supports, of mechanism extensible to determine the plane of the upper support connecting said supports and comprising a plurality of cylinders carried by said lower support, said cylinders being arranged in longitudinally spaced pairs and the cylinders of each pair being transversely spaced, and pistons in said cylinders connected to said upper support.

7. The combination with upper and lower supports, of mechanism extensible to determine the plane of the upper support connecting said supports and comprising a plurality of cylinders connected with one of said supports, said cylinders being arranged in longitudinally spaced pairs and the cylinders of each pair being transversely spaced, pistons in said cylinders, and a transverse pivot connecting the pistons of each pair with the other of said supports.

8. The combination with upper and lower supports, of mechanism extensible to determine the plane of the upper support connecting said supports and comprising a plurality of cylinders connected with one of said supports, said cylinders being arranged in longitudinally spaced pairs and the cylinders of each pair being transversely spaced, pistons in said cylinders connected to the other of said supports, an exhaust passage leading from each of said pairs of cylinders, and a valve for controlling all of said exhaust passages.

9. The combination with upper and lower supports, of supporting mechanism including fluid supporting means extensible by movement of one of said supports and connecting said supports, and means for sup-

porting said upper support from said lower support independently of said extensible means and comprising uprights rising from said lower support and means for detachably connecting said upper support to said uprights.

10. The combination with upper and lower supports, of supporting mechanism including fluid supporting means connecting said supports and extensible by movement of said upper support, and means for supporting said upper support from said lower support at different heights independently of said extensible supporting means.

11. The combination with upper and lower supports, of supporting mechanism including fluid supporting means extensible by movement of one of said supports and connecting said supports, uprights rising from said lower support, legs depending from said upper support, and clamps connecting said legs and uprights.

12. The combination with a wheeled truck, a unitary mining machine carried thereby, and mechanism intermediate said machine and truck for supporting the former at different elevations relative to the latter and including extensible fluid supporting mechanism comprising elements whose elevations change on movement of the mining machine, of constantly operative driving connections between said machine and truck for propelling said truck from said machine irrespective of the vertical position of the latter.

13. The combination with a wheeled truck and a machine carried thereby, of extensible supporting means connecting said machine and truck extended by successive opposite tilting movements of said machine to elevate the latter bodily relative to the truck, and driving connections between said machine and truck for propelling said truck, said connections being constructed and arranged to remain continuously operative irrespective of relative movement of said machine and truck.

14. The combination with a wheeled truck, a frame supported thereon and providing a guideway, a mining machine slidably and swivelly supported by said guideway for longitudinal movement and for swinging movement, and supporting means connecting said frame and truck adjustable to permit raising and lowering of said guideway and machine relative to the truck of driving connections between said machine and truck for propelling the truck wheels from the machine including a shaft on said frame, a shaft on said truck, and connections between said shafts constantly operative throughout the range of raising and lowering.

15. The combination with a wheeled truck, a unitary mining machine of a type adapted to cut upon its bottom upon a mine bottom carried thereby, and means including a

5 hydraulic supporting means for permitting raising and lowering of said machine, of driving connections between said machine and truck constantly operative throughout the range of said raising and lowering for propelling said truck wheels from said machine.

16. The combination with a wheeled truck, a unitary mining machine carried thereby, 10 and manually operable oscillating means permitting raising and lowering of said machine as a whole relative to said truck to permit cutting of differently elevated parallel kerfs, of driving connections between said machine and truck constantly operative throughout the range of said raising and lowering of said machine for propelling said truck wheels from said machine.

17. In combination, a wheeled truck, a 20 mining machine support thereon having means for longitudinally slidably receiving a mining machine and for permitting swiveling thereof, means adjustable to permit raising and lowering of said support relative to said truck, and truck wheel driving connections connectible with a machine on said support and operative throughout the range of raising and lowering including sprockets, one on said support and one coaxial with a 30 truck wheel, and a flexible connection between said sprockets permitting separation and approach thereof while maintaining a driving relation.

18. In combination, a wheeled truck, a 35 support thereon having swiveled machine supporting means thereon adapted slidably to receive a unitary mining machine, supporting means permitting raising and lowering of said support relative to the truck, 40 and truck wheel driving connections connectible with a machine in one position on said support and operative throughout the range of said raising and lowering.

19. The combination with a wheeled truck, 45 of a swiveled mining machine receiving guideway thereon, adjustable supporting means between said truck and guideway permitting varying the height of the latter relative to the truck or the angle thereof to the horizontal, and truck wheel driving connections adapted to be driven by a machine on 50 said guideway and operative throughout the range of said adjustable supporting means.

20. In combination, a wheeled truck, a 55 support thereon adapted slidably to receive a unitary mining machine, means oscillatable to effect raising and lowering of said support bodily relative to the truck, and truck wheel driving connections connectible with the machine in one position on said support and 60 operative throughout the range of said raising and lowering.

21. In combination, a wheeled truck, a 65 support thereon having machine supporting means thereon adapted slidably to receive a

unitary mining machine, means including a plurality of telescopic members oscillatable to effect raising and lowering of said support relative to the truck, and truck wheel driving connections connectible with the machine in 70 one of its positions on said support and operative throughout the range of said raising and lowering.

22. In a mining apparatus, a wheeled truck, a support, a mining machine mounted 75 thereon and adapted to be swiveled relative thereto, and vertically extensible hydraulic supporting means disposed between said truck and said support and including elements secured to the support and truck and so extensible to vary the height of the support by relative movement between the machine and truck.

23. In a mining apparatus, a support, cutting mechanism thereon, and means including hydraulic supporting means and operable by movement of said cutting mechanism in a plane selectively to vary the elevation or angle in elevation of the latter.

24. In a mining apparatus, a support, cutting mechanism thereon, and means including hydraulic supporting means and operable by movement of the cutting mechanism in a given plane to effect elevation of the latter and operative to support the latter at an 95 angle to its normal position when adjusted thereto to permit cutting of relatively inclined kerfs.

25. In a mining apparatus, a support, a mining machine mounted thereon and adapted 100 to be swiveled relative thereto, and mechanism including fluid supporting means operable by movement of the mining machine in a given plane to effect elevation of the latter.

26. The combination with spaced supports, 105 of mechanism including fluid supporting means interposed between said supports operable by oscillating movement of one of said supports to elevate the same.

27. In a mining apparatus, a support, cutting mechanism thereon including a projecting bar, and mechanism including fluid supporting means for said cutting mechanism manually operable by oscillating movement of said bar to effect elevation.

28. The combination with upper and lower supports, and a mining machine on said upper support provided with a cutter bar, of fluid supporting means connecting said supports extensible by pivotal movement of said cutter bar in a vertical plane and operative to support said mining machine at different heights.

29. In a mining apparatus, a support, cutting mechanism thereon, and fluid supporting means for said cutting mechanism adapted to support the latter at different heights and adjustable by pivotal movement of said cutting mechanism in a vertical plane, said supporting means comprising a plurality of 125

- spaced cylinders connected to said support and pistons in said cylinders connected with said cutting mechanism.
30. In a mining apparatus, a support, a mining machine thereon, and extensible fluid supporting means extended by successive tilting movements of the mining machine in a vertical plane.
31. The combination with upper and lower supports, of mechanism extensible by movement of one of said supports connecting said supports and comprising a plurality of longitudinally spaced cylinders connected to one of said supports and having inwardly opening check valves, pistons in said cylinders, and transverse pivots connecting said pistons with the other of said supports.
32. The combination with upper and lower supports, of mechanism extensible by movement of one of said supports connecting said supports and comprising a plurality of spaced cylinders connected to one of said supports, valve controlled exhaust passages leading from said cylinders, pistons in said cylinders, and transverse pivots connecting said pistons with the other of said supports.
33. The combination with upper and lower supports, of mechanism extensible by movement of one of said supports connecting said supports and comprising a plurality of spaced cylinders connected to one of said supports, and having inwardly opening check valves, valve controlled exhaust passages leading from said cylinders, pistons in said cylinders, and transverse pivots connecting said pistons with the other of said supports.
34. The combination with upper and lower supports, of mechanism extensible by movement of one of said supports connecting said supports and comprising a plurality of spaced cylinders connected to one of said supports, pistons in said cylinders, transverse pivots connecting said pistons with the other of said supports, and a liquid reservoir communicating with said cylinders.
35. The combination with upper and lower supports, of mechanism extensible by movement of one of said supports connecting said supports, and comprising a plurality of spaced cylinders connected to one of said supports, pistons in said cylinders, transverse pivots connecting said pistons with the other of said supports, a liquid reservoir communicating with said cylinders, and inwardly opening check valves for controlling communication between said cylinders and reservoir.
36. The combination with upper and lower supports, of mechanism extensible by movement of one of said supports connecting said supports comprising a plurality of spaced cylinders connected to one of said supports, pistons in said cylinders, transverse pivots connecting said pistons to the other of said supports, a liquid reservoir, and valve controlled exhaust passages leading from said cylinders to said reservoir.
37. The combination with upper and lower supports, of mechanism extensible by movement of one of said supports connecting said supports and comprising a plurality of spaced cylinders connected to one of said supports, pistons in said cylinders, transverse pivots connecting said pistons with the other of said supports, a liquid reservoir, inlet passages connecting said reservoir and cylinders and having check valves opening toward said cylinders, and valve controlled exhaust passages leading from said cylinders to said reservoir.
38. The combination with upper and lower supports, of mechanism extensible by successive tilting movements of one of said supports in a vertical plane and connecting said supports and comprising a plurality of spaced cylinders carried by said lower support and pistons in said cylinders connected to said upper support.

In testimony whereof I affix my signature.

MORRIS P. HOLMES.
